Specification of Letters Patent. Patented Jan. 29, 1918.

Application filed June 16, 1917. Serial No. 175,075.

To all whom it may concern:

Be it known that we, CHARLES B. KING and FRANK RENZENBERGER, citizens of the United States, residing at Marion, in the county of Marion and State of Ohio, and GRANT HOLMES, a citizen of the United States, residing at Danville, in the county of Vermilion and State of Illinois, have invented certain new and useful Improvements in Excavating-Machines, of which the following is a specification, reference being had therein to the accompanying drawings.

This invention relates to excavating machines and more particularly to a machine for excavating and loading coal.

In many parts of this country coal deposits are found close to the surface of the earth and this coal is removed by first stripping therefrom the overburden of earth and rock, and then removing the coal with suitable excavating machines, such as an ordinary steam shovel. The use of the ordinary excavating machine for this purpose is open to several objections, such, for example, as the tendency of the usual excavating dipper to break up the coal to a greater extent than is desirable. Further, in these coal deposits there frequently occur partings of considerable depth which are filled with earth, or other foreign matter, and in some fields there occur ridges of clay which extend vertically through the vein, breaking it up into a plurality of parts. With the ordinary excavating machine it is very difficult, if not impossible, to remove all the coal from the vein without removing and mixing with the coal part of the earth, or clay, found in these partings, or ridges.

The object of the present invention is to provide a machine which will remove the coal without unduly breaking the same, and which can be so manipulated so as to remove all the coal from the vein without mixing it either with earth, or other foreign matter, and to provide such a machine which will be simple in its construction, positive in its operation, and of strong, durable character. To this end it is a further object of the invention to provide a machine of this character having a dipper supporting device, the movements of which are controlled by a boom; and further to so mount the

dipper supporting device that it may be vertically adjusted bodily to enable the dipper to operate successively along a plurality of substantially straight parallel lines, thereby enabling the coal to be removed in layers to the full depth of the vein without altering the position of the machine as a whole. A further object of the invention is to provide such a mechanism which can be mounted upon an ordinary steam shovel, in place of the usual excavating mechanism, and operated by the power plant of such a shovel, thus enabling the owner of an ordinary power shovel to convert the same into a coal mining machine by substituting for the usual excavating mechanism that herein shown and described. Other objects of the invention will appear as the mechanism is described in detail.

In the accompanying drawings Figure 1 is a side elevation, partly broken away, of a machine embodying our invention; Fig. 2 is a plan view, partly broken away, of such a machine; Fig. 3 is a sectional view of the upright frame on the line 3-3 of Fig. 4, on an enlarged scale; Fig. 4 is a front elevation of the upright frame with the boom and dipper arm in section; Fig. 5 is a horizontal sectional view of the upright frame taken on the line 5-5 of Fig. 4; and Fig. 6 is a front elevation of the excavating dipper.

In these drawings we have illustrated one embodiment of our invention and have shown the same as applied to an ordinary rotary steam shovel, which constitutes the supporting structure for the operating devices, but it will be understood that the device may be mounted upon a supporting structure of any suitable character; and further that, while the present machine is designed primarily for excavating and loading coal, it is not limited to such a use, but can be used to good advantage for other work where a similar character of excavation is required, for example, in road work.

As here illustrated, the supporting structure comprises a base 1 which is supported by wheels 2 and has rotatably mounted thereon a platform 3 on which is mounted the steam plant 4, which furnishes power for operating the various mechanisms for propelling the machine as a whole, for oper-

ating the excavating devices and for rotating the frame. To enable the frame to be rotated an annular rack 5 is mounted on the base and meshing with said rack is a pinion 6 carried by a shaft 7 journaled on the frame 3 and driven through suitable gearing from an engine 8. A pair of engines 9 connected with a common engine shaft 10 serve to operate the propelling, hoisting and excavating devices. This shaft 10 is connected through suitable gearing with a vertical shaft 11 arranged centrally of the platform 3, which extends through the base 1 and is geared to a horizontal propelling shaft 12 which in turn is geared to the rear axle 13 of the machine. The mechanism so far described is of standard steam shovel construction, and, as stated, is here shown merely for the purpose of illustration. Mounted at the forward end of the frame 3, which constitutes the supporting structure therefor, is a dipper supporting device which carries an excavating dipper, and is of such a character that this dipper may move toward and from the supporting structure in a substantially straight line, and further, the dipper supporting device is of such a character that the dipper may be moved along a substantially horizontal plane, or at such an angle to the horizontal as may be desired. This dipper supporting device is preferably supported at its outer end by a boom, which controls the movements thereof. The dipper supporting device may be of any suitable character, but as here shown comprises a rigid arm 14 pivotally mounted at its rear end on the supporting structure, and having mounted thereon for movement longitudinally thereof an excavating dipper 15. This dipper may be of any suitable character and may be connected with the dipper supporting device in any suitable manner, and in the construction here shown it has a substantially flat bottom and is provided at its forward or cutting edge with dipper teeth 16. The dipper is preferably connected with the dipper supporting device, or arm, by a carriage which will, of course, be of such a construction as to accommodate it to the character of the dipper supporting device, but is here shown as comprising a pair of side plates 17 arranged on opposite sides of the dipper arm and connected one to the other by bolts 18 arranged above and below the dipper arm, and which may, if desired, be provided with rollers 19 to engage the upper and lower edges of the arm and facilitate the movements of the carriage. The dipper proper is preferably of a rigid construction and is pivotally connected with the dipper supporting device to permit the forward end thereof to move downward to discharge the contents therefrom. In the present instance the carriage 17 is provided with a base plate, or casting, 20, to which the upper rear edge of the dipper is pivotally connected as shown at 21. The rear wall of the dipper is provided at its upper edge with a forwardly extending part 22 which is provided at its forward end with keepers, or apertured lugs 23, adapted to receive latch bars 24 mounted on the carriage. These latch bars are held normally in their operative positions by springs 25 and have connected therewith a cable 26 leading to the supporting structure, or such other point from which it is desired to control the dumping of the dipper. The dipper is provided along its lateral edges with forwardly tapering side walls 27 which have a wedge-like action upon the coal and serve to lift that part of the coal beneath which the dipper extends and to break the same loose from the adjacent portions of the vein of coal. In some instances the coal is more or less pliable and the layer of coal as a whole will be lifted by the tapered edges of the dipper, and in order to separate that part of the coal which is engaged by the dipper from the adjacent portions of the layer we have provided the forwardly extending part 22 of the dipper with a depending forwardly inclined rib 28, which will be engaged by the rear edge of the layer of coal as it moves along the rearwardly inclined side walls of the dipper, and will force the same downward, thus serving to break the coal after the manner shown in Fig. 6. Forward or excavating movement is imparted to the dipper by means of a cable 29 which is connected at one end to the forwardly extending upper part, 22, of the dipper, thence extending about a sheave 33 at the forward end of the boom, thence rearwardly to a hoisting drum 34 mounted on a shaft 35 on the platform 3, which is driven through suitable gearing from the engine shaft 10. Rearward or return movement is imparted to the dipper by means of a cable 36 connected with the carriage 17, and extending rearwardly to a drum 37, also mounted on the shaft 35. The drums 34 and 37 are loosely mounted on the shaft 35 and are connected thereto by a suitable clutch, or clutches, so arranged that when one drum is connected with the shaft for rotation therewith to impart movement to the dipper the other drum will be loosely mounted on the shaft and free to rotate to permit its cable to pay out as the dipper is moved by the other cable. The coal constituting a vein is usually divided into layers by partings, which are approximately parallel and which ordinarily extend substantially horizontally. In the forward movement of the dipper the cutting edge is caused to travel along one of these partings and to remove the layer, or layers, of the coal lying above that particular parting. After all the coal of one layer, which can be reached by the dipper, has been

removed the dipper is operated along another parting on a lower level. In order that the dipper may be operated along the substantially parallel lines formed by the 5 partings between the superimposed layers of coal we have so mounted the dipper supporting device, or arm, 14, that it can be bodily adjusted in a vertical direction without altering the position of the supporting 10 structure. This adjustment may be effected in various ways, preferably by pivotally mounting the heel of the dipper supporting device upon a suitable member, or members, which are vertically adjustable and which 15 can be held in their vertically adjusted positions during the excavating operation. In the present embodiment of the invention we have shown the dipper arm as having a bifurcated rear end, the arms 38 of which are 20 pivotally mounted between ears 39 carried by guide blocks 40 which, as here shown, are in the form of nuts adapted to receive vertical screws 41. These guide blocks, or nuts, are slidably mounted in suitable guide-ways 25 formed in an upright frame, or gauntlet, secured to the forward end of the supporting structure. As here shown the gauntlet comprises two pairs of channel-irons 42, the channel irons of each pair having their flat 30 faces opposed one to the other and spaced apart to form the guide-ways for the guide-blocks 40 and rigidly secured at their lower ends to a base member, or casting, 43, which is provided with a lug 44 adapted to extend 35 between and to be bolted to the lugs 45 of the frame 3, which usually carry the boom of the steam shovel. This construction enables the gauntlet, or upright frame, to be very easily and quickly attached to and re- 40 moved from the base 3. It is rigidly braced at its upper end by means of longitudinal frame members or channels, 46, extending between the same and the usual upright frame, or gauntlet, 47, of the steam shovel 45 mechanism. It will be obvious, however, that where the mechanism is used with a different type of supporting structure the gauntlet may be mounted and braced in any suitable manner. The upright screws 41 are 50 journaled at their upper ends in suitable bearing blocks 48 and each has secured thereto at its upper end a beveled gear 49 with which meshes a beveled gear 50 rigidly secured to a transverse shaft 51 journaled in 55 bearings 52 carried by the upright frame. The arrangement of the beveled gears here shown requires right and left-hand screws, but obviously any suitable arrangement may be employed. The shaft 51 is driven from 60 a suitable part of the power mechanism on the frame 3 and is here shown as provided with a sprocket wheel 53 connected by a sprocket chain with a sprocket wheel 54 on a shaft 55, which shaft is carried by brackets 65 56, rigidly secured to the frame members or braces 46. A second sprocket wheel 57 is also rigidly secured to the shaft 55 and is connected by a chain 58 with a sprocket wheel 59 on the shaft 35, this sprocket wheel being connected with the shaft by suitable 70 clutch mechanism so that it can be operated at will. The clutch mechanisms for controlling the devices on the shaft 35 are not illustrated in detail as they are of ordinary construction and form no part of the present 75 invention. It will be apparent, therefore, that the heel of the dipper arm may be vertically adjusted and the dipper supporting device as a whole moved vertically so as to support the same substantially parallel 80 with the surface of the coal at different heights with relation to the supporting structure. To relieve the screws 41 of strain the nuts 40 are provided at their forward edges with flanges 60 which bear against the forward edges of the guide members, or channel-irons, 50, and transmit the strain from the dipper arm to the upright frame. The inner flanges 60 are connected together to unite the two slide blocks and their flanges 85 into a single supporting structure for the dipper arm. To this end the inner flanges are provided with out-turned portions 61, forming ears, between which are mounted sheaves 62 and 63 and extending upwardly 90 from these ears are brackets 64 between which are mounted sheaves 65 and 66. These two pairs of sheaves, together with a pair of sheaves 67 and 68, which are mounted on the dipper arm at a point in front of 100 the axis of the arm, serve to guide the cables 29 and 36 and maintain the same in proper relation to the dipper arm in the various adjusted positions of the latter.

While the dipper supporting device may be controlled and manipulated in various manners, we prefer to utilize a boom for this purpose, and to so connect the boom with the dipper supporting device that it will relieve the latter of lateral strains on the swinging of the dipper to dumping position, and will also add to the dipper an additional weight, which is desirable in order that the latter may be held firmly in engagement with the work. The boom as here shown comprises two forwardly converging members 69, pivotally mounted between lugs 70 on the frame 3 of the supporting structure and having mounted at their outer ends a sheave 71. A hoisting cable 72 extends about the sheave 71 and about sheaves 73 mounted at the upper end of the upright frame, or gauntlet, and is connected at one end with the point of the boom and at the other end with a hoisting drum 74 on the frame 3. The connection between the forward end of the boom and the adjacent end of the dipper supporting device is such as to cause the latter to move laterally with the boom and to permit of 115 120 125 130

the relative longitudinal movement of the ends of the two parts during the hoisting operation. As the boom and the dipper supporting device are mounted on different centers, the distance between their ends changes as they move about their respective axes, and is further affected by the vertical adjustment of the dipper supporting device. To permit of this relative movement, we have, in the present construction, connected the two parts by means of a pair of links 75, pivotally connected at their upper ends with the boom and at their lower ends with the dipper supporting device, the connections being preferably made by mounting the links on the shafts which carry the sheaves 71 and 33, respectively.

The operation of the mechanism will be readily understood from the foregoing description of the several parts hereof. Briefly it is as follows: The machine is placed at the edge of the vein on a surface some distance below the top of the vein. The dipper supporting device is elevated a distance corresponding to the depth of the vein and is so positioned that the edge of the dipper may be caused to enter a parting spaced at a suitable distance from the top of the vein, the thickness of the layer of coal above the parting along which the dipper operates preferably being such that the dipper will be filled by a movement equal to its length. With the dipper in this position the pull cable 29 is operated to force the dipper along the parting and to fill the same with coal. After the dipper is full the boom is hoisted by means of the cable 72 and carries with it the outer end of the dipper supporting device. During the hoisting operation the pull cable 29 is further operated to carry the dipper toward the end of the dipper supporting device, and the boom is swung laterally, in the present instance by rotating the frame 3, to carry the dipper to the point of discharge, which ordinarily is a coal car. When the dipper has been moved above the point of discharge the latch bars 24 are tripped by means of the cable 26 and the dipper permitted to drop to discharge its load into the car, the pull-cable having been slackened off to permit of this movement of the dipper. As the dipper supporting device is returned to operating position the dipper is retracted by means of the cable 36 to a point where it may be again filled, and it may, if desired, be again moved to its operative, or latched, position by exerting a pull on the cable 29, but in the ordinary operation of the device the dipper supporting arm will lower the dipper so that the edge thereof will engage the surface of the coal as the dipper is being retracted and will thus cause the same to be moved to its latched position.

65 While we have shown and described one

embodiment of our invention we wish it to be understood that we do not desire to be limited to the details thereof as various modifications will occur to a person skilled in the art.

Having now fully described our invention, what we claim as new and desire to secure by Letters Patent, is:

1. In a machine of the character described, an upright frame having forwardly opening vertical guide-ways, a structure extending transversely to said guide-ways and having parts slidably mounted therein, said structure and said guide-ways having co-operating parts to hold the structure against turning movement relatively to said guide-ways and to cause the transverse strains on said structure to be transmitted to the edges of said guide-ways, means for moving said structure along said guide-ways and for holding the same in adjusted positions, a dipper supporting device pivotally mounted on said structure, a dipper carried by said device and movable lengthwise thereof, and means for actuating said dipper. 70 75 80

2. In a machine of the character described, an upright frame comprising two pairs of parallel members spaced apart to form guide-ways, blocks slidably mounted between said parallel members, having flanges to engage the forward edges of said parallel members and having lugs extending beyond the forward edges of said parallel members, means for moving said blocks along said guide-way and for holding the same in their adjusted positions, a dipper supporting device pivotally connected with the lugs of said blocks, an excavating dipper carried by said device and movable lengthwise thereof, and means for actuating said dipper. 85 90 100 105

3. In a machine of the character described, an upright frame having forwardly opening vertical guide-ways, screws extending lengthwise of said guide-ways, 110 slide-blocks mounted in the respective guide-ways and having threaded apertures to receive the respective screws, said slide blocks having flanges to engage the forward edges of said guide-ways, means for rotating said 115 screws, a dipper supporting device pivotally mounted on said slide blocks, a dipper mounted on said supporting device for movement lengthwise thereof, and means for actuating said dipper. 120

4. In a machine of the character described, an upright frame having parallel members to form guide-ways, slide blocks mounted in the respective guide-ways, having flanges to engage the forward edges of said parallel 125 members and having lugs extending beyond said parallel members, means for connecting said slide blocks one to the other, screws arranged lengthwise of said guide-ways and extending through the respective slide 130

- blocks, means for rotating said screws, a dipper supporting device pivotally mounted on the lugs of said slide-blocks, a dipper slidably mounted on said device, and means 5 for actuating said dipper.
5. In a machine of the character described, a supporting structure having a pair of lugs, an upright frame comprising a base plate adapted to rest on said lugs and having a 10 lug extending between the first-mentioned lugs and secured thereto, parallel members extending upwardly from said base plate to form guide-ways, slide blocks mounted in said guide-ways, screws arranged lengthwise of said guide-ways and extending through the respective slide blocks, means 15 for actuating said screws, a dipper supporting device pivotally mounted on said slide blocks, a dipper mounted on said device, and 20 means for actuating said dipper.
6. In a machine of the character described, a supporting structure capable of swinging movement, a dipper supporting device pivotally mounted on said structure, an excavating dipper carried by said device and movable lengthwise thereof, means for actuating said dipper, means to vertically adjust the axis of said dipper supporting device, and a connection between said dipper 25 supporting device and said structure, other than said pivotal connection, to relieve said pivotal connection from lateral strains.
7. In a machine of the character described, a supporting structure, a vertically adjustable member carried by said structure, means 30 for actuating said vertically adjustable member, a dipper arm connected with said vertically adjustable member, an excavating dipper carried by said arm, means for moving said dipper lengthwise of said arm, and means for imparting lateral springing movement to said dipper supporting arm, comprising a connection between said arm and said supporting structure independent of 35 said vertically adjustable member, to relieve the latter of lateral strains.
8. In a machine of the character described, a supporting structure, a dipper supporting device mounted on said structure, an excavating dipper carried by said device and movable lengthwise thereof, a boom mounted 40 on said supporting structure and connected with said supporting device at a point remote from said structure, and means to impart movement to said boom to elevate the outer end of said dipper supporting device.
9. In a machine of the character described, a supporting structure, a dipper supporting device mounted on said structure, an excavating dipper carried by said device and movable lengthwise thereof, a boom mounted 45 on said supporting structure, a connection between said boom and said dipper supporting device to hold the latter against lateral movement relatively to said boom,
- and means to actuate said boom to cause it to impart movement to said dipper supporting device.
10. In a machine of the character described, a supporting structure, a dipper supporting device mounted on said structure, an excavating dipper carried by said device and movable lengthwise thereof, a boom mounted 50 on said supporting structure and connected with said dipper supporting device at a point remote from said structure, and means to actuate said boom to elevate the outer end of said dipper supporting device, to impart lateral swinging movement to said boom and to move said dipper toward the outer end of its supporting device.
11. In a machine of the character described, a supporting structure, a dipper supporting device pivotally mounted on said structure and capable of bodily vertical movement 55 relatively thereto, an excavating dipper carried by said device and movable lengthwise thereof, means to impart vertical movement to said dipper supporting device, a boom pivotally mounted on said supporting structure and connected with said dipper supporting device at a point remote from said supporting structure, and means to impart pivotal movement to said boom.
12. In a machine of the character described, a supporting structure, a vertically adjustable member mounted on said structure, a rigid dipper supporting device pivotally mounted on said adjustable member, an excavating dipper carried by said device and movable lengthwise thereof, a boom pivotally mounted on a fixed axis on said supporting structure, and a connection between 60 said boom and said dipper supporting device near the outer end thereof.
13. In a machine of the character described, an upright frame, a vertically adjustable member carried by said frame, a dipper supporting device mounted on said member, an excavating dipper carried by said device and movable lengthwise thereof, a boom mounted 65 on a fixed axis near the foot of said upright frame and connected with said dipper supporting device near the outer end thereof, and means to move said boom about its axis.
14. In a machine of the character described, an upright frame having a guide-way, a slide-block mounted in said guide-way, an adjusting screw for said slide-block, a dipper supporting device pivotally mounted on said slide-block, a dipper carried by said device for movement lengthwise thereof, a boom pivotally mounted near the foot of said upright frame and connected with the dipper supporting device near the outer end thereof, and means to actuate said boom and said dipper.
15. In a machine of the character described, a supporting structure, a boom pivotally 120 mounted on said structure, a dipper supporting device pivotally mounted on said boom, a boom pivotally mounted near the foot of said upright frame and connected with the dipper supporting device near the outer end thereof, and means to actuate said boom and said dipper.

- 6 mounted on said structure, a dipper supporting device pivotally mounted on said structure, a link connecting the outer end of said boom to the outer end of said dipper supporting device, an excavating dipper carried by said dipper supporting device for movement lengthwise thereof, and means for actuating said boom and said dipper.
16. In a machine of the character described, 5 a supporting structure comprising a rotatable member, a dipper supporting device pivotally mounted on said member, an excavating dipper carried by said device and movable lengthwise thereof, a boom pivotally mounted on said member and connected with 10 said dipper supporting device at the outer end thereof, means for imparting pivotal movement to said boom to elevate the outer end of said dipper supporting device and 15 for actuating said dipper, and means for rotating said frame.
17. In a machine of the character described, 20 a supporting structure comprising a rotatable frame, an upright frame mounted on said rotating frame, a vertically adjustable member carried by said upright frame, a dipper supporting arm pivotally mounted on said member, an excavating dipper supported by said arm and movable lengthwise 25 thereof, a boom pivotally mounted on said rotatable frame, a link connection between the outer end of said boom and the outer end of said dipper supporting device, and 30 means for actuating said boom and said dipper.
- 35
18. In a machine of the character described, a supporting structure, a dipper supporting device connected with said structure, an excavating dipper carried by said dipper supporting device for movement lengthwise thereof, said dipper having its side walls tapered toward the forward edge thereof and having a rearwardly and downwardly extending rib arranged above, and between the planes of, said side members, and means to 40 actuate said dipper.
19. In a machine of the character described, the combination with a rotatable frame having at one end thereof lugs to receive an excavating boom, of a frame comprising a base 45 member having a part to fit between the lugs on said rotatable frame, and upright members rigidly secured to said base member, said upright members being arranged to form a guide-way, a slide-block mounted in 50 said guide-way, means for moving said slide-block along said guide-way, a dipper supporting device connected with said block, an excavating dipper carried by said device and movable lengthwise thereof, a boom pivotally mounted near the foot of said frame 55 and connected with said dipper supporting device near its outer end, and means for actuating said boom and said dipper.
- In testimony whereof we, hereunto affix 60 our signatures.
- 65
